UNITED STATES PATENT OFFICE.

EDMOND H. FISHACK, OF GYPSUM, OHIO.

MACHINE FOR MANUFACTURING PLASTER-BOARD.

1,253,676.

Specification of Letters Patent. Patented Jan. 15, 1918.

Application filed January 11, 1915. Serial No. 1,656.

To all whom it may concern:

Be it known that I, EDMOND H. FISHACK, a citizen of the United States, residing at Gypsum, in the county of Ottawa and State of Ohio, have invented a new and useful Machine for Manufacturing Plaster-Board, of which the following is a specification.

This invention has reference to improvements in machines for manufacturing plaster board, and its object is to provide a machine for the expeditious manufacture of plaster board.

In accordance with the present invention the machine is so constructed that the boards when manufactured are confined under pressure while setting; the boards are produced successively in the form of a pile upon a support arranged to be lowered intermittently to extents determining the thickness of the boards; means are provided whereby the boards are formed in a casing or mold which may be in part collapsed or removed, so that the complete pile of boards may be taken out of the machine at one operation, and this may be further facilitated by the construction of the lowering support in the form of a car capable of being moved into and out of the machine upon suitable tracks. The invention also contemplates the use of separating sheets for the boards, which sheets may be so constructed as to form the surfaces of the boards into desired shapes, and the invention also contemplates the application of power for producing the requisite pressure in a manner to limit the pressure to a predetermined amount.

The invention will be best understood from a consideration of the following detailed description, taken in connection with the accompanying drawings forming a part of this specification, with the further understanding that while the drawings show a practical form of the invention, the latter is not confined to any strict conformity with the showing of the drawings, but may be changed and modified so long as such changes and modifications are within the scope of the appended claims.

In the drawings:

Figure 1 is a front elevation of a machine embodying the present invention.

Fig. 2 is a side elevation thereof as seen from the left hand side of Fig. 1.

Fig. 3 is a central vertical section of the machine as viewed in Fig. 1.

Fig. 4 is a section on the line 4—4 of Fig. 2.

Fig. 5 is a section on the line 5—5 of Fig. 2.

Fig. 6 is a bottom plan view of the car 60 constituting the lowering support.

Fig. 7 is a fragmentary section of one of the division plates drawn on a much larger scale than the other figures of drawing.

While in many of its details the machine of the present invention may be variously constructed, a simple and efficient construction is illustrated in the drawings. There is a main frame made of upright corner posts 1 with top and bottom cross beams 2, 3, respectively, all of which may be made of structural steel, and preferably channel or other angular steel. Supported on the bottom beams 3 are closely adjacent spaced beams 4 also of channel steel, and these beams carry a bearing 5 on which is mounted a bevel pinion 6 axially screw threaded for the passage of a screw rod 7, which latter is located in the central vertical axis of the frame. This rod carries at its upper end a head 8 of sufficient lateral extent for a purpose to be described. In describing the screw rod 7 as upright and in all other expressions of position used herein reference is had to an installed machine.

The corner posts 1 carry other cross pieces 9 upon which are placed track rails 10 for receiving the wheels 11 of a truck 12 shown separately in Fig. 6, and this truck comprises a platform 13 supported by marginal side beams 14 and end beams 15, and these last-named beams carry journal boxes 16 for axles 17 in turn carrying the wheels 11. Extending between and fast to the side beams 14 are intermediate cross beams 18 suitably spaced apart to be both engaged by the head 8. The beams 4 carry a journal standard 19 supporting a journal bearing 20 for a shaft 21 which extends from a point adjacent to the rod 7 to the exterior of the main frame where it is journaled in a suitable bracket 22. At the end next to the rod 7 the shaft 21 carries a bevel pinion 23 in mesh with the pinion 6 and at the outer end the shaft 21 is provided with means for its actuation which may be in the form a hand crank 24 or any other means may be employed, and the crank 24 is therefore to be taken as indicative of either hand means or power means for the turning of the pinion.

6, which, being in the form of a nut, causes the raising or lowering of the rod and with it the head 8, and when a truck 12 is in position to have its cross beams 18 engaged by the head 8, then on the rising movement of the rod the truck is lifted to the extent desired.

Extending between appropriate cross beams 2 at the top of the frame are spaced beams 25 from which depend hangers 26 carrying other beams 27 at their lower ends. At about midway of the length of the beams 25 there is secured a block 28 forming a thrust block for a bevel gear 29 traversed by an upright screw rod 30 located in the upright central axis of the frame and in alignment with the rod 7. The beams 27 carry journal bearings 31 for respective shafts 32, 33, each having a bevel pinion 34, 35, respectively, in mesh with the gear 29. These shafts 32 and 33 each pass through a journal bearing 36 mounted on a cross beam 37 at each end of the main frame, and near the top thereof. Exterior to the main frame the shaft 32 carries a clutch member 38 and the shaft 33 carries a similar clutch member 39. Each of these clutch members is what is known as a friction release clutch, and since such structures are readily obtainable upon the market, it is unnecessary to show or describe them in detail. In action they operate until the resistance reaches a predetermined point when they no longer drive the driven member.

35 The rod 30 carries at its lower end a follower 40 having laterally outstanding arms or brackets 41 on opposite sides each terminating in an eye 42 slidable along a guide rod 43 mounted between respective pairs of corner posts and supported at the upper ends in the beams 37 and at the lower ends in other beams 44 similar to the beams 37, but located at a correspondingly lower level. The ends of the rods 43 may be held in 45 blocks or supports 45 made fast to the respective beams.

Extending between the corner posts in parallel relation to the beams 44 are other beams 46, these last-named beams being approximately on a level with the top of the car or truck 12 when supported upon the rails 10.

Made fast to the beams 44 and 46 on one end of the main frame is a plate 47 forming one end of a mold and made fast to these same beams and the corresponding beams at the other side of the frame is another plate 48 forming one side of the mold. The other end and side of the mold are 60 formed by other corresponding plates 49 and 50, respectively, but neither of these plates is made permanently fast to the frame. The four plates when assembled constitute a rectangular mold open top and 65 bottom and of a size and shape to readily

but snugly receive the platform 18 of the car or truck 12, so that this platform or support, together with the remainder of the car may be elevated inside of the mold to the top thereof by a suitable manipulation of the shaft 21, thereby impelling the screw nut 6 to raise the rod 7 and with it the head 8, and the truck or car supported thereby, said car being indicative of any other suitable movable device.

The beams 44 and 46 adjacent to the end plate 49 of the mold carry cam members 51 each provided with a handle 52 and movable about a pivot pin 53, and these cam members are so related to the end plate 49 of the mold that they may be moved to clamp this plate tight against the corresponding face or side members 48 and 50, the latter being grooved, as indicated at 54, to firmly seat the edges of the end plate 49. Extending between the corner posts of the corresponding side of the main frame to the end plate 49 are supporting bars 55 upon which the lower edge of the end plate 49 may rest. Mounted upon pivot pins or bolts 56 traversing the flanges of the corner posts 1 adjacent to the face plate 50 of the mold are cams 57 each provided with a manipulating handle 58 and so related to the mold plate 50 that on a proper manipulation of the cams the mold plate is firmly lodged against the end plates 47 and 49. The end plate 50 is furthermore provided with chains 59 each fastened at one end to the plate and at the other end terminating in a pin 60, 100 while the follower 40 has holes 61 formed therein in position to receive the pins 60 for a purpose to be described.

In Fig. 3 the mold chamber is shown as filled by a pile or stack of plaster boards 62, and these boards are shown as separated by plates 63, one of which is shown in Fig. 7 as corrugated. These plates are preferably of metal, of which tin or galvanized iron may be taken as an example, and the corrugations may be taken as indicative of any indentations or figures formed on the plates to be impressed in the corresponding faces of the plaster boards.

Let it be assumed that the mold chamber is empty, and that the end plate 49 of the mold chamber has not yet been clamped in place, and that the face plate 50 has been raised by the elevation of the follower 40 with the pins 60 of the chains 59 in the holes 61, the clamp cams 57 being also in the loosened or disengaged position. Now, the car or truck 12 is moved upon the tracks 10 until within the space defined by the mold chamber at the lower end thereof, after which the follower 40 is lowered until the face plate 50 has reached its lowermost position which may be determined by the bar 55 and a stop 64 on a level with the bar 55. The cams 51 and 57 are manipulated 130

to clamp the movable plates 49 and 50 tightly in place and the crank or other actuating means for the shaft 21 is operated to cause the head 8 to engage the beams 18 and elevate the car or truck until it is spaced from the top of the mold chamber by a distance equal to the proposed thickness of the plaster board, the follower 40 having been in the meantime raised sufficiently to be out of the way. A plaster board is now formed in the top portion of the mold upon the platform 13 and a division plate 63 is laid upon the formed board, after which the truck is lowered a distance corresponding to the thickness of the next plaster board. This operation of lowering the support successively by predetermined distances and the introduction of the separating sheets continues until the mold is filled with plaster boards and the separating sheets, the showing of the latter being exaggerated in Fig. 3 for the purposes of illustration. Pressure is applied by the follower 40 as needed and when the mold chamber is filled with plaster boards, the pressure is maintained until the pile of plaster boards has set. The pressure of the follower 40 may be regulated to a nicety by the employment of releasing friction clutches which produce a pressure to the predetermined point, and then maintain it thereat without increase of the pressure. The screw 7 and the driving means for the screw may be so arranged that one or two or a certain predetermined number of turns of the shaft 21 will produce a movement of the lowering support equal to the desired thickness of the plaster board.

When the pile of plaster boards has become set the cams 51 and 57 are released and the pins 60 are introduced into the holes 61, whereupon the follower 40 is elevated, the face plate 50 of the mold being lifted with it out of the way of the truck or car and the pile of plaster boards thereon, while the side member 49 being released from the cams controlling it offers no impediment to the removal of the car with the pile of plaster boards from the mold, and then another car may be introduced and the operation repeated, while the first car is being transported to a desired point and unloaded.

By the present invention plaster boards may be made successively of even thickness and consistency and may be permitted to set and harden while under pressure, so that when released from such pressure they will retain the form imparted to them. The space wherein the plaster boards are molded is always at the top of the mold and uniform, this being accomplished by a predetermined lowering of the support for the plaster boards, so that there is ultimately formed a pile made up of plaster boards all of the same thickness. The collapsible mold permits the formation of the pile of boards

in a minimum space and their removal without the necessity of further lowering or of raising the pile after completion. By separating the plaster boards by metallic sheets to which they do not adhere each board is separated from the others, and, furthermore, any configuration desired may be imparted to the surface of the board. A predetermined pressure is important and this is advantageously brought about by the use of the releasing clutches which permit the quick operation of the device without leaving the matter of proper pressure to chance or the judgment of the operator of the machine, for the pressure may be fixed by the preadjustment of the automatic releasing friction clutch.

What is claimed is:—

1. In a machine for manufacturing plaster board, an upright fixed mold open top and bottom, a support of a size to enter the mold and movable laterally beneath the mold into and out of alinement therewith, means for bodily raising the support from a position below the mold into the mold through the open bottom thereof and for raising and lowering the support within the mold to varying extents, a follower of a size to bodily enter the mold through the top thereof, and means for moving the follower into and out of the mold toward and from the support when the latter is within the mold.

2. In a machine for manufacturing plaster board, an upright fixed mold open top and bottom, a support movable laterally beneath the mold into and out of alinement therewith, means for moving the support bodily lengthwise of the mold through the open bottom thereof, a follower movable into and out of the mold toward and from the support when the latter is in the mold, and means for applying pressure to the follower and automatically holding such pressure to a determined degree while the support is maintained in a fixed position.

3. In a machine for manufacturing plaster board, an upright fixed mold open top and bottom, a car or truck movable laterally with respect to the mold into and out of underlying relation to the open bottom of the mold, and means for raising and lowering the car or truck bodily to varying extents up and down within the mold, whereby a stack of superposed articles may be formed in the mold with the car constituting a support for such stack and each article constituting a support for the next article above it.

4. In a machine for manufacturing plaster board, an upright fixed mold open top and bottom, a car or truck movable laterally with respect to the mold into and out of underlying relation to the open bottom of the mold and of a size to bodily enter the mold through the open bottom thereof, means for

125
130

moving the car or truck bodily up and down in the mold, whereby the car constitutes a support for articles formed in the mold, and a follower movable into and out of the mold 5 through the open top thereof in opposition to the car or truck.

5. In a machine for the manufacture of plaster boards, an upright fixed mold open top and bottom and of a capacity to hold a

- 10 pile of plaster boards, a supporting frame for the mold, a support for the boards movable laterally with respect to the length of the mold into and out of coincidence with the bottom of the mold, said support being 15 of a size to move into the mold through the open bottom thereof, means for moving the support for the boards to varying extents lengthwise through the mold, whereby the plaster boards may be successively formed 20 in superposed order within the mold upon the support, a follower carried by the supporting frame for the mold and provided with means for moving said follower into the mold through the top of the latter 25 against a pile of plaster boards on the support for said boards while the support is held stationary, and means carried by the supporting frame for the mold for applying pressure to and automatically maintaining a predetermined pressure against the 30 pile of plaster boards within the mold until the plaster boards have set.

6. In a machine for the manufacture of plaster boards, a mold of a capacity to hold 35 a pile of plaster boards, a support movable through the mold lengthwise of the latter and provided with means whereby the support may be moved by steps for the formation of the boards successively in the mold 40 to produce a pile thereof on the support, a follower movable into engagement with the topmost one of the plaster boards and automatic means for applying a predetermined pressure through the follower to the plaster 45 boards and holding such pressure until the plaster boards have set.

7. In a machine for manufacturing plaster board, a mold open top and bottom and having one side removable, a support movable laterally into and out of the mold through the space provided for by the removable side, means for moving the support up and down of the mold, a follower movable into and out of the upper end of the mold toward 55 and from the support when the latter is in the mold, and means for applying pressure to the follower and automatically holding such pressure to a predetermined degree.

8. In a machine for manufacturing plaster 60 board, a mold having one side removable, a car or truck movable into and out of the mold through the opening provided by the removal of the side of the mold, said car or truck conforming in size to the cross-sec- 65 tional area of the mold, and means for mov-

ing the car or truck in the mold in a direction perpendicular to its movement into and out of the mold through the open side of the latter.

9. In a machine for manufacturing plaster 70 board, a mold having one side removable, a car or truck movable into and out of the mold through the opening provided by the removal of the side of the mold, said car or truck conforming in size to the cross sec- 75 tional area of the mold, means for moving the car or truck lengthwise of the mold, and a follower movable into the mold in opposition to the car or truck.

10. In a machine for manufacturing 80 plaster board, a mold having one side removable, a car or truck movable into and out of the mold through the opening provided by the removal of the side of the mold, said car or truck conforming in size to the 85 cross sectional area of the mold, means for moving the car or truck lengthwise of the mold, a follower movable into the mold in opposition to the car or truck, and automatic means for exerting pressure upon the 90 follower to a predetermined extent.

11. In a machine for manufacturing plaster board, a mold, a car or truck of a size to enter the mold, and means for moving the car or truck to various extents 95 lengthwise of the mold.

12. In a machine for manufacturing plaster board, a mold having adjacent portions movable toward and from the molding space and one of said portions removable from the mold, means for holding the removable members in position against internal pressure in the mold, a car or truck movable laterally into and out of the mold through the space provided for by the removable member, means for moving the car or truck lengthwise of the mold, and a follower movable into and out of the mold in opposition to the car or truck.

13. In a machine for manufacturing 110 plaster board, a mold having two adjacent portions movable toward and from the molding space, one of said portions being removable from the mold, a car or truck movable into and out of the mold through the space 115 provided for by the removable member, means for moving the car or truck lengthwise of the mold by steps each corresponding to the thickness of a plaster board, means for locking the movable members of the 120 mold in position against the action of pressure exerted against them from the inside of the mold, a follower movable into and out of the mold in opposition to the car or truck, and means for applying and sustaining 125 pressure upon the follower against plaster board sustained by the car or truck, said pressure applying means being constructed to automatically produce the pressure to a predetermined degree.

14. In a machine for manufacturing plaster board, a mold chamber having a removable side member, a follower adapted to enter the mold chamber, and means for connecting the removable side member to the follower for the movement of the removable member away from the mold chamber and the return of the removable member to the mold chamber.
15. In a machine for the manufacture of plaster board, a mold chamber, a bottom member for the mold chamber comprising a truck or car of a size to move bodily wholly into the interior of the mold, and means positioned to engage the truck or car when within the mold chamber and raise and lower it therein.
16. In a machine for the manufacture of plaster board, a mold having adjacent portions movable toward and from the mold chamber within the mold and one of said portions being removable from the mold, means for holding the movable mold members against the action of pressure exerted thereagainst from the interior of the mold, a supporting member for plaster boards movable into and out of the mold through the space provided by the removal of the removable member, and means for raising and lowering the supporting member when within the mold.
17. In a machine for the manufacture of plaster board, a mold having adjacent portions movable toward and from the mold chamber within the mold and one of said portions being removable from the mold, means for holding the movable mold members against the action of pressure exerted thereagainst from the interior of the mold, a supporting member for plaster boards movable into and out of the mold through the space provided by the removal of the removable member, and means for raising and lowering the supporting member when within the mold, said machine being also provided with a follower movable into and out of the top of the mold.
18. A machine for the manufacture of plaster board comprising a suitable frame, a mold carried by the frame with members in fixed relation thereto and other adjacent members in movable relation thereto, one of said members being removable from the mold, a track carried by the frame below the mold, a truck or car movable on the
- track and constructed to form a supporting member when within the mold, and introducible into and removable from the mold through the space provided by the removal of the removable member, an elevating and lowering means carried by the frame in position to engage the car and lift it toward the top of the mold, and lower it by successive steps corresponding to the thickness of a plaster board, a follower carried by the frame and movable into and out of the upper end of the mold, means for attaching the removable member to the follower, and pressure applying means connected to the follower for causing the latter to exert a predetermined maintained pressure upon the plaster boards within the mold until the material of the plaster boards is set.
19. A machine for the manufacture of plaster board, comprising a suitable frame, a mold carried by the frame with members in fixed relation thereto and other adjacent members in movable relation thereto, one of said members being removable from the mold, a track carried by the frame below the mold, a truck or car movable on the track and constructed to form a supporting member when within the mold, and introducible into and removable from the mold through the space provided by the removal of the removable member, an elevating and lowering means carried by the frame in position to engage the car and lift it toward the top of the mold, and lower it by successive steps corresponding to the thickness of a plaster board, a follower carried by the frame and movable into and out of the upper end of the mold, means for attaching the removable member to the follower, and pressure applying means connected to the follower for causing the latter to exert a predetermined maintained pressure upon the plaster boards within the mold until the material of the plaster boards is set, the movable members of the mold being provided with clamp means for holding them in operative position against pressure exerted on them from the interior of the mold.
- In testimony that I claim the foregoing as my own, I have hereto affixed my signature in the presence of two witnesses.
